UNITED STATES PATENT OFFICE.

NAPOLEON CARON, OF NASHUA, NEW HAMPSHIRE.

LOOM-SHUTTLE-THREAD GUIDE.

Application filed February 9, 1924. Serial No. 691,778.

To all whom it may concern:

Be it known that I, NAPOLEON CARON, a citizen of the United States, residing at Nashua, in the county of Hillsborough and 5 State of New Hampshire, have invented new and useful Improvements in Loom-Shuttle-Thread Guides, of which the following is a specification.

My present invention has reference to 10 loom shuttles, and has for its object to simplify and improve the thread guide for such shuttles.

A further object is to produce a thread 15 guide for loom shuttles of a construction whereby the shuttle may be readily threaded by hand, and which includes a friction device of felt or flannel for securing the required tension upon the thread.

A still further object is the production of 20 a thread guide for shuttles formed from a relatively short metal strip secured in one side of the throat portion of the shuttle, inward of the vertical and lateral slots in the nose thereof that provide guides in the 25 threading of the shuttle, and which strip has its lower portion rounded upon itself to provide a substantially elliptical thread guide, the inner wall of which being slightly spaced from the strip proper, and the end 30 wall of which being slightly spaced from the initial bend in the said rounded portion so that the thread may be readily slipped between the side of the strip and the said inner rounded portion of the guide, the 35 outer rounded wall of the guide being notched to provide a pocket for a friction strip of felt or flannel.

To the attainment of the foregoing, reference is to be had to the drawing which 40 accompanies and which forms part of this application.

In the drawing:—

Figure 1 is a top plan view of one end of 45 a loom shuttle illustrating the application of the improvement therein.

Figure 2 is a side elevation of the end of the shuttle provided with the improvement.

Figure 3 is a top plan view of the said 50 end of the shuttle with parts broken away and parts in section, the improvement being also in section.

Figure 4 is a sectional view on the line 4—4 of Figure 1.

Figure 5 is a perspective view of the improvement.

The shuttle is of the ordinary construction and is indicated by the numeral 1. The shuttle, at one of the nose ends 2 thereof, is formed with a central depression which I 60 will term a throat and which is indicated by the numeral 3. The vertical angularly arranged thread guide slot through the nose is indicated by the numeral 4 and the horizontal slot by the numeral 5. The horizontal 65 slot communicates with a depression in one side of the nose, and in this depression there is secured an outer thread guide of the usual construction.

My improved thread guide is formed from 70 a relatively short strip of suitable metal, having one end formed with an angle portion or ear 6 seated in a suitable depression at one side of what I have termed the throat 75 in the nose 3, and secured thereto by means 80 of 7. The strip, from its angle end or ear is in contacting engagement with one of the side walls provided by the throat 3. This straight portion of the strip is indicated by the numeral 8. The straight portion 8 of the strip is rounded outwardly upon itself, as at 9, and is from thence coiled to provide a substantially elliptical guide eye 10. The inner wall of the guide eye, that is the wall 85 next to the straight portion 8 of the strip, is spaced therefrom, and the end of the elliptical guide eye terminates approximately in a line with the longitudinal center of the rounded portion 9, but is slightly spaced therefrom. This permits of the thread 90 being readily passed into the eye. The outer side of the eye is formed with a slot 11. This slot provides a pocket for the ends 95 of a frictional element in the nature of a strip of felt or flannel, indicated by the numeral 12.

Preferably I secure in the lower wall of the throat, in a line with the outer side of the guide eye 10 a cross sectionally rounded pin 13, and this pin is disposed in a line 100 with the outer guide eye 14 of the shuttle.

It is believed that the foregoing description, when taken in connection with the drawing, will fully set forth the construction of my improvement and its advantages 105 to those skilled in the art to which such inventions relate and that further detailed description will not be required.

Having described the invention, I claim:

1. A thread guide for loom shuttles 110 formed from a relatively short strip of metal having a straight side to be arranged against

one of the side walls of the throat in the nose portion of the shuttle, and having its lower portion rounded and continued in elliptical formation against the bottom and 5 opposite side wall of the throat, the inner wall of the elliptical portion of the guide being spaced from the straight side thereof and the terminal edge thereof being disposed approximately in a line with the longitudinal center of the first mentioned rounded 10 portion but slightly spaced therefrom.

2. A thread guide for loom shuttles formed from a relatively short strip of metal having a straight side to be arranged against 15 one of the side walls of the throat in the nose portion of the shuttle, and having its lower portion rounded and continued in elliptical formation against the bottom and opposite side wall of the throat, the inner wall of the 20 elliptical portion of the guide being spaced from the straight side thereof and the terminal edge thereof being disposed approximately in a line with the longitudinal center of the first mentioned rounded portion but slightly spaced therefrom, and the outer side wall of the said elliptical portion being 25 notched to provide a pocket, and a fabric frictional agent in said pocket and entering the bore of the guide.

3. A thread guide for loom shuttles 30 formed from a relatively short strip of metal having a straight side to be arranged against one of the side walls of the throat in the nose portion of the shuttle, and having its lower portion rounded and continued in elliptical formation against the bottom and opposite side wall of the throat, the inner wall of the elliptical portion of the guide being spaced from the straight side thereof and the terminal edge thereof being disposed approximately in a line with the longitudinal center of the first mentioned rounded portion but slightly spaced therefrom, and a frictional fabric in the guide. 40

4. A thread guide for loom shuttles 45 formed from a relatively short strip of metal having one end bent to provide an ear for the reception of a securing element, the opposite end of the strip being rounded elliptically upon itself, the inner wall of the elliptical portion being slightly spaced from the straight portion of the strip, and the terminal of the said elliptical portion being disposed approximately in a line with the longitudinal center of the initial rounded portion. 50

In testimony whereof I affix my signature.
NAPOLEON CARON. 55
